DIAPER BAG

Mary Hagglund, 921 Chambers, Ottawa, Ill.

Filed Apr. 20, 1964, Ser. No. 79,584

Term of patent 14 years

(Cl. D58—2)

FIG. 1

I claim:

The ornamental design for a diaper bag, substantially as shown.
